UNITED STATES PATENT OFFICE.

MAX HERSKOVITZ, OF CHICAGO, ILLINOIS, ASSIGNOR TO PEERLESS LIGHT COMPANY, OF CHICAGO, ILLINOIS, A CORPORATION OF MAINE.

ELECTRIC-SOCKET STRUCTURE.

Application filed April 28, 1920. Serial No. 377,148.

To all whom it may concern:

Be it known that I, MAX HERSKOVITZ, a citizen of the United States, residing at Chicago, in the county of Cook and State of Illinois, have invented a new and useful Improvement in Electric-Socket Structures, of which the following is a specification.

My invention relates, as to one feature thereof, to electric socket structures of a character involving a portion at which the socket-structure is supported, as for example in the case of so-called candle-sockets; and as to another feature thereof, to electric sockets in general whether, or not, adapted to be used as parts of socket-structures of the character above stated.

One of my objects is to provide a novel, simple and inexpensive construction of electric-socket of the character above stated. Another object is to provide a novel, simple and inexpensive construction of socket for use in general and to which current-conducting wires for supplying current to the socket, may be economically and readily attached.

Referring to the accompanying drawings:—

Figure 1 is a view in side elevation of an electric-socket constructed in accordance with my invention and adapted to form a portion of an electric candle-socket structure. Figure 2 is a similar view taken at a right angle thereof. Figure 3 is a section taken at the line 3 on Fig. 1 and viewed in the direction of the arrows. Figure 4 is a perspective view of one of the current-conducting elements forming parts of the socket. Figure 5 is an enlarged section taken at the line 5—5 on Fig. 1 and viewed in the direction of the arrow. Figure 6 is a similar view taken at the line 6—6 on Fig. 2 and viewed in the direction of the arrow. Figure 7 is a broken section taken at the line 7 on Fig. 6 and viewed in the direction of the arrow. Figure 8 is a view like Fig. 5, of another structure embodying the invention; Figure 9 is a perspective view of the upper end of one of the two similar arms of the supporting yoke with the shell with which they engage, omitted.

In the construction illustrated in Figs. 1 to 7 inclusive, the socket is formed of a shell 8 which is made preferably of insulating material, such, for example, as paper board or fiber board, or any other desirable mate-

rial, provided in the form of a tube, shown as open at its opposite ends and into one end of which the screw-shell of the socket, represented at 9 and provided to receive the screw-plug of an incandescent electric lamp, 60 and form one of the contacts of the socket, is shown to extend, the shell 9 preferably extending slightly short of the end of the shell 8. The shell 9 is provided at its inner end with a disk 10 of insulating material 65 carrying a center-contact 11 shown as formed of a plate 12 bent to present a contact-making portion 13, the plate 12 being held to the disk 10, as by a metal eyelet 14 extending through these parts. The shell 9 has 70 electrically connected therewith, as by soldering, one end of a metal current-conducting element 15 of strip form, which extends along the inside of the shell 8 and is equipped at its opposite end with a binding-screw 16. A similar current-conducting element represented at 17, connects at its inner, reduced, end 18, with the center-contact 11, as by soldering it in the opening in the eyelet 14, this element extending along the inside of the shell 8 and being provided at its outer end with a binding-screw 19. In accordance with the illustrated embodiment of my invention, the shell 8 is slit as indicated at 20, at opposite sides thereof circumferentially, and the material between these slits and the lower end of the shell inwardly buckled, as represented at 21, the lower, binding-screw-equipped, ends of the elements 15 and 17 extending into the spaces 75 presented at the exteriors of these buckled portions, as represented in Figs. 3 and 5, whereby the binding-screws 16 and 19, while being partially protected by the shell 8, are nevertheless rendered readily accessible for 80 the attachment thereto of electric-current-conducting wires leading from any suitable source of electric-current supply. The parts described are preferably assembled to the positions shown and described by attaching 85 the elements 15 and 17 to the screw part of the shell 9 and the center-contact 11, respectively, and these parts so assembled, assembled with the shell 8 to cause them to be 90 surrounded by the latter. With the parts 100 of the structure thus assembled, cement, represented at 22, and of any suitable character non-conductive of electric current, as for example the cement used in the wiring of electric chandeliers is poured into the end 110

of the shell 8 opposite that into which the screw-shell 9 extends, to fill this end of the shell 8, as shown, thereby firmly cementing together the parts described, in assembled condition.

The socket illustrated in Figs. 1 to 7 inclusive, is also formed with a yoke-shaped member 28 containing an aperture, preferably threaded, in the lower cross-member 29 of the frame at which the socket structure would be supported in use as by screwing it upon the threaded nipple usually provided in electric fixtures of the electric candle type. The frame 28 is preferably made of metal and the upper ends of the arms thereof are formed with tongues 30 formed by slitting the metal of these arms. The upper ends of the arms referred to extend upwardly into the interior of the shell 8 along the side walls of the latter, these portions of the arms being preferably curved as shown in Fig. 7, and the tongues 30 are bent outwardly, thence upwardly and at their upper extremities, inwardly, to extend into openings 31 in the shell 8, the material of this shell between the openings 31 and the lower edge thereof being preferably closely embraced by these tongues as shown.

It will be understood that in forming the socket shown the yoke-member 28 would be assembled with the shell 8, as stated, before the cement 22 is introduced into the shell, thereby also cementing the upper ends of the arms of the yoke 28 in position, and firmly anchoring them in place, the shaping of the arms at their upper ends as stated, enhancing the anchoring effect.

The feature of connecting the frame 28 with the socket structure, as described, causes the structure to be very rigid and possess a high degree of durability at relatively low cost.

It will be understood that in so far as the yoke feature 28 of the structure is concerned, it may be employed in sockets intended for use otherwise than as candle-sockets, in which case the yoke 28 which would probably be somewhat shorter, would form the support for the socket whether the socket extends in the upright position shown or is inverted, or extends at an angle to the vertical.

Figure 8 is illustrative of another of the various forms in which the invention may be provided, the structure shown being of a form more nearly resembling the ordinary form of socket in that it is formed with a metal enclosing casing. In this construction, the internal parts are shown as of the same construction as those shown in Fig. 5 and the same numerals are used to designate the several parts. The metal casing referred to is represented at 32, it being formed of two telescoping sections 33 and 34, the section 33 carrying the internal parts referred

to and the section 34, which may be threaded as indicated at 35 for attachment to a support, forming a cap-portion. The lower end of the section 33 is of enlarged diameter as shown at 36 and in the assembling of the 70 said internal parts therewith, the cement 22 not only cements the various internal parts in position, but also, by extending between the shell 8 and the section 33, as shown, rigidly cements the casing 33 to the shell 8. 75

It may be here stated that by constructing a socket member as above described, it may be made very economically and possesses a high degree of durability and strength, the invention thereby providing a socket construction which may be used in many situations where much more expensive constructions of sockets are now required to be used. 80

While I have illustrated and described certain constructions embodying my invention, I do not wish to be understood as intending to limit it thereto as the same may be variously modified and altered without departing from the spirit of the invention. 85

What I claim as new and desire to secure 90 by Letters Patent is—

1. In an electric socket, the combination of a shell of insulating material, electrical contacts, current-conducting elements in said shell connected with said contacts, respectively, the end of said shell being slit, with the portions thereof adjacent to said slits being inwardly buckled, the ends of said current-conducting elements opposite those connected with said contacts being located 95 within said buckled portions, moldable material, non-conductive of electric current, and having the property of setting, located in the end of said shell opposite that adjacent said contacts, and in which said current-conducting elements are embedded, and devices on the ends of said current-conducting elements opposite those connected with said contacts positioned to be accessible at the buckled portions of said shell for attaching electric-current-conducting wires thereto. 100

2. In an electric socket, the combination of a shell of insulating material, a screw shell extending into one end of said first-named shell and presenting a side contact and a center contact, current-conducting elements connected with said contacts, respectively, the end of said first-named shell being slit, with the portions of this shell adjacent thereto inwardly buckled, the ends of said current-conducting elements opposite those connected with said contacts being located 115 within said buckled portions, moldable material non-conductive of electric current, and having the property of setting, located in the other end of the tube and in which said current-conducting elements are imbedded, and devices on the ends of said current-conducting elements opposite those con- 120

125

130

nected with said elements and positioned to be accessible at the buckled portions of said first-named shell for attaching current-conducting wires to said elements.

5 3. In a socket structure, the combination of a shell and a supporting member having arms which extend upwardly into overlapping position relative to said shell, with tongues on said arms bent outwardly and 10 thence upwardly into clamping engagement with said shell.

4. In a socket structure, the combination of a shell and a supporting member having arms which extend upwardly into overlapping position relative to said shell, with 15 tongues bent outwardly and upwardly to extend at their lower portions below the lower edge of said shell, and clamping said shell.

20 5. In a socket structure, the combination of a shell and a supporting member having arms which extend upwardly into overlapping position relative to said shell, with tongues bent outwardly, thence upwardly 25 and thence inwardly to extend into openings in said shell, said tongues clamping said shell.

6. In a socket structure, the combination of a screw shell and a center contact, a second shell in which said screw shell and 30 center contact are positioned, a supporting

member having arms which extend upwardly into said shell, with devices securing said arms to said second shell, electric current-conducting elements connected with said 35 screw shell and said center contact, respectively, located within said second shell, and moldable material, non-conductive of electric current and having the property of setting, located in the end of the shell opposite 40 that occupied by said screw shell and contacting with said arms, with said elements and with said screw shell and rigidly holding these parts in assembled relation, said electric current-conducting elements 45 projecting through said moldable material.

7. In a socket structure, the combination of a shell, electrical contacts, a supporting member having arms which extend upwardly into said shell, the upper ends of said arms 50 being of a cross-sectional form other than flat, electric-current-conducting elements connected respectively with said contacts and located within said shell, and moldable material, non-conductive of electric current, 55 and having the property of setting, located in said shell and imbedding the upper ends of said arms and said current-conducting elements and holding these parts and said contacts in rigid relation to said shell.

MAX HERSKOVITZ.
